CLAIM

The ornamental design for a reservoir assembly for a product dispenser, as shown and described.

DESCRIPTION

FIG. 1 is a perspective view of a reservoir assembly for a product dispenser showing our new design;

FIG. 2 is a front view thereof;

FIG. 3 is a rear view thereof;

FIG. 4 is a right side view thereof, the left side view being a mirror image thereof;

FIG. 5 is a top view thereof; and,

FIG. 6 is a bottom view thereof.
